OVERHEAD DOOR CONSTRUCTION

Alvin V. Rowe, Galesburg, Ill., assignor to Rowe
Manufacturing Company, Galesburg, Ill., a cor-
poration of Illinois

Application October 11, 1945, Serial No. 621,781

6 Claims. (Cl. 160—201)

1

This invention relates generally to an overhead door construction and more particularly to overhead door constructions wherein a switch mechanism is employed in association with the horizontal portions of the guide track structure.

One of the problems which confronts the manufacturer of overhead door structures is that of producing a door which may be shifted between closed vertical position and open overhead position with a minimum amount of available headroom. The present invention concerns itself with the solution of the aforesaid problem and to this end contemplates in combination with conventional guide track structures a switch mechanism of extremely simple and practical design adapted to selectively control communication of the horizontal track portion with the usual curved portion and a further portion extending forwardly from the horizontal portion.

More specifically the invention contemplates in combination with hingedly connected door sections shiftable between vertical and horizontal positions of a switch mechanism having a novel control arrangement to facilitate the shifting of a movable switch member. In this connection it is contemplated to employ a trip, or latching device, which is operable as an incident to the shifting of the door sections whereby to cause positive and instantaneous shifting of a movable switch member.

It is a further object of the present invention to provide a device as set forth above, wherein the movable parts of the switch mechanism and the latching means forming a part thereof are pivotally mounted in such a manner as to insure freedom of movement at all times, and to accomplish this, substantially frictionless pivotal bearings are contemplated.

It is also an object of the present invention to provide in combination with the shiftable hingedly connected door sections and track structures, as set forth above, a switch device or mechanism which, as the door sections move from their horizontal to their vertical position, may be automatically unlatched by a trigger device so as to instantaneously and positively establish communication between the horizontal track portion and a forwardly extending track portion and thereby permit the uppermost follower members, or rollers, on the door to move forward. As the door sections shift upwardly from their vertical closed position the uppermost guide rollers move rearwardly along the portion of the track extending forwardly from the horizontal portion and this arrangement reduces to a minimum the

2

amount of headroom necessary for efficient operation; in fact the invention makes it possible to install an overhead door construction in instances where the available headroom is not more than two inches.

The foregoing and other objects and advantages will be more apparent from the following detailed description when considered in connection with the accompanying drawings wherein:

Fig. 1 is a fragmentary elevational view of the inner side of the door when the hingedly connected sections thereof occupy their vertical door closing position;

Fig. 2 is an enlarged fragmentary vertical sectional view taken substantially along the line 2—2 of Fig. 1 to more clearly illustrate the relative positions of the door follower members, or rollers, and the shiftable elements of the switch mechanism;

Fig. 3 is an enlarged fragmentary vertical sectional view taken substantially along the line 3—3 of Fig. 1 disclosing the opposite side of the switch mechanism and track portions associated therewith;

Figs. 4—6 inclusive, are enlarged views of the switch mechanism and associated track portions as illustrated in Fig. 2, Fig. 4 disclosing the uppermost door section as it is passing from the curved track section to the horizontal section but prior to the opening of the shiftable switch member, Fig. 5 being a view similar to Fig. 4 showing the door section in a further advanced position with the latch opening mechanism carried by the upper door section about to move past the trigger plate, and Fig. 6 illustrating the latch actuating abutment as it moves downwardly into engagement with the trigger plate so as to release the latch member and thereby permit the automatic shifting of the switch member to its lower position;

Fig. 7 is an horizontal sectional view taken substantially along the line 7—7 of Fig. 4;

Fig. 8 is a vertical sectional view taken substantially along the line 8—8 of Fig. 4;

Fig. 9 is a perspective view of the trigger plate detached from the track structure; and

Fig. 10 is a perspective view of the shiftable switch member which serves in its downward position to guide the uppermost rollers to and from the horizontal track section.

Referring now to the drawings more in detail wherein like numerals have been employed to designate similar parts throughout the various figures, it will be seen that the invention contemplates an overhead door construction which

includes a plurality of hingedly connected door sections 12, 14, 16 and 18 of Fig. 1. The door section 12 will be hereinafter referred to as the uppermost door section and the door section 18 as the lowermost door section. These sections are connected by suitable hinges 20, and in the vicinity of each of these hinges 20 is a track follower member, or roller, 22. The guide rollers 22 will hereinafter be referred to as intermediate guide rollers, or follower members, to distinguish from an upper roller 24 associated with each upper corner of the uppermost door section 12 and lower guide rollers 26 associated with the lower corners of the lowermost door section 18.

When the door sections 12-18 inclusive, occupy their vertical door closing position as shown in Figs. 1 and 2, the intermediate guide rollers 22 and the lower guide rollers 26 are positioned within a vertical portion 28 of guide track structures. Each vertical track portion 28 communicates with a curved portion 30 which in turn is adapted to communicate, or connect, with an horizontal track portion 32 through the agency of a switch mechanism designated generally by the numeral 34. The upper guide rollers 24 carried by the upper door section 12 rest within the outer extremity of a forwardly extending or auxiliary track portion 36 when the door sections occupy their vertical door-closing position. The forward or outer extremity of the track portion 36 is curved downwardly so that when the uppermost section 12 reaches its final closing position it will be sealed against a header 38 of the building structure in which the door construction is installed. An horizontal portion of the track 36 extends rearwardly from the above-mentioned curved portion and is adapted to communicate, or connect, with the horizontal track portion 32 by means of the aforesaid switch mechanism 34.

The structural and functional characteristics of the switch mechanism 34 may best be understood by describing the operation of the door sections as they shift between their vertical door-closing position and the upper open or overhead position. Assuming that the door sections occupy their normal door-closing position, as shown in Figs. 1 and 2, and a force is applied so as to urge the door sections upwardly, the upper rollers 24 will move upwardly and rearwardly in the curved section of the track portion 36 effecting the immediate disengagement or unsealing of the upper margin of the door section 12 from the header 38. From the curved section of the track portion 36 the rollers 24 move horizontally within the horizontal section and ultimately reach a shiftable member 40 of the switch mechanism 34. A detailed disclosure of this shiftable switch, or track member, 40 will be found in Fig. 10. When the switch member 40 occupies the position shown in Figs. 2 and 4, it serves to direct the upper guide rollers 24 between the auxiliary track portion 36 and the horizontal main track portion 32. It will be noted that the left extremity of the shiftable switch member 40 is pivotally mounted on a knife edge 42. A flange 44 extends over one side of the plate 46 upon which the knife edge 42 is formed, and a U-shaped portion of a strip 48 is positioned on the opposite side of the plate 46. (See Fig. 4.) Sufficient play is provided between the flange 44 and the U-shaped portion 48 so as to provide a free pivotal connection and permit pivotal movement of the member 40 between the lower solid-line position and the upper dotted-line position as illustrated in Fig. 2. By this arrangement free pivoting of the switch

member, or arm, 40 is always assured. Any tendency for rust or other foreign matter to collect within the pivotal area of the knife edge 42 is free to fall downwardly away from said knife edge. A pin 50 traverses the U-shaped portion of the strip 48 so as to prevent upward disengagement of the switch arm from the pivotal knife edge 42. It will be noted that the switch arm 40 is urged toward its lower position by a coil spring 52 which extends between a hook 54 on the strip 48 and a tab 56 bent laterally of a mounting plate 58. This mounting plate 58 serves as the means for coupling the track portions 36, the upper part of the curved track portion 30 and the forward part of the horizontal track portion 32 as a unit.

As the door sections continue to move toward their open overhead position the upper guide rollers 24 move rearwardly within the horizontal track portions 32 and eventually the intermediate rollers 22 associated with the hinge in the vicinity of the adjacent margins of the door section 12 and the door section 14 move into engagement with an L-shaped portion 60 of the strip 48. This causes the switch element to be shifted upwardly to the position shown in Fig. 6. As the switch element 40 reaches this position a trip or latch mechanism, about to be described, is conditioned so as to prevent subsequent downward shifting of the switch member until said latch mechanism is automatically shifted during the movement of the door sections from open toward closed position.

The latch mechanism, just referred to, includes a trip or latching plate 62 which is shown in detail in Fig. 9. The plate 62 is provided with an arcuate slot 64 which accommodates a pin 66. This pin provides a pivotal support for the plate 62 as illustrated in Figs. 3 and 4. As the switch member 40 is shifted upwardly through the agency of the rollers 22, as just described, an arm 68 formed integral with the switch member 40 is urged upwardly against the underside of an arm 70 on the plate 62. This causes the plate 62 to pivot in a clockwise direction, as viewed in Fig. 4, and a counterclockwise direction, as viewed in Fig. 3, about the pin 66 now positioned in the upper extremity of the arcuate slot 64. The upward movement of the arm 60 is sufficient to clear the arm 70 and as this occurs the arm 70 falls downwardly to the position illustrated in Fig. 6, thereby preventing downward shifting of the switch member 40. Pressure of the arm 68 against the arm 70 of the plate causes the outer extremity of the arm 70 to bear against an abutment 72 (Fig. 7) formed integral with and extending laterally of the track coupling plate 58. With the switch arm 40 in this position the following intermediate rollers 22, as well as the lower rollers 26, are directed from the curved track portion 30 into the horizontal track portion 32.

Thus far the functioning of the switch mechanism to enable proper movement of the guide rollers into the horizontal track portions has been described. It will now be assumed that the door sections are to be shifted from their open overhead position toward their closed vertical position. With the shiftable switch member 40 occupying the position shown in Fig. 6, the lowermost rollers 26 and the intermediate rollers 22 are directed from the horizontal track portion 32 into the curved track portion 30. Immediately following the entrance of the uppermost intermediate rollers 22 into the curved track portion

30, an abutment 74 carried by the uppermost door section 12 is brought into engagement with a depending finger portion 76 of the plate 62, as clearly illustrated in Fig. 5. Engagement of the abutment 72 with the finger 76 causes the plate 62 to be pivoted about the pin 66 and the plate is rotated in a clockwise direction as viewed in Fig. 5. This causes the instantaneous shifting of the arm, or finger, 70 away from the underside of the arm 68 permitting the sudden downward shifting of the switch member 40 to the position illustrated in Fig. 4. Thus as the upper rollers 24 approach the switch mechanism, the switch member 40 is positioned so as to direct said rollers from the horizontal track portion 32 into the forwardly extending or auxiliary track portion 36.

Attention is directed to the movement of the plate 62 when the finger portion thereof is engaged by the abutment 74 as the door sections shift upwardly from closed to open position. By the time the abutment 74 has moved upwardly into engagement with the finger 76, the shiftable switch member 40 will have been shifted upwardly and latched in position as previously described. The engagement of the abutment or projection 74 with the finger 76 causes the plate 66 to rotate in a counterclockwise direction, as viewed in Fig. 5, about the fulcrum point established by the engagement of the arm or finger 70 with the fixed abutment 72, as shown in Fig. 7. The arcuate slot 64 in the plate permits this limited, free movement of the plate 62. This free tilting, or shifting, of the plate merely serves to enable the abutment 74 to pass upwardly without tripping the latch mechanism. In other words, as the abutment 74 moves upwardly and engages the finger 76 of the plate 62, said finger serves as a pawl which permits passage of the abutment without disturbing the latched position of the shiftable switch member 40. As the finger 76 automatically moves downwardly after the passage of the abutment 74 it occupies a position in the path of said abutment during the subsequent closing of the door sections. During this closing movement the abutment 74 engages the finger 76 as previously described, thereby causing instantaneous unlatching of the switch member. The downward shifting of the plate 62 is assured by employing a coiled spring 78 which is interposed between the plate 62 and the track coupling plate member 58. It will be understood, however, that both the downward shifting of the plate 62 and the downward shifting of the switch member 40 takes place under the action of gravity, the coil springs 52 and 78 being used in instances where it is deemed essential to assure instantaneous action. It will also be noted that the point of fulcrum between the finger, or arm, 70 and the abutment 72 provides a bearing which is free from the accumulation of rust, foreign matter and the like. By having this point of contact any accumulation of rust or dirt tends to fall downwardly, away from the point of fulcrum and hence free pivoting of the plate 62 about this point is assured at all times.

From the foregoing it will be apparent that the present invention contemplates an overhead door construction of improved, practical design. Another difficult problem which confronts manufacturers of overhead doors is that of reducing to a minimum the number of automatically shiftable parts in order to assure efficient operation over

an extended period of time, and to avoid as far as possible unnecessary noise in operation. The switch mechanism described herein is of extremely practical construction in that the number of moving parts are few and the mechanism may be assembled or disassembled with a minimum amount of effort and skill. The bearings which provide the pivotal points are so constructed as to positively preclude accumulation of rust or other foreign matter. In other words, once the mechanism is installed it need not be lubricated from time to time in order to insure continuous satisfactory operation. This is extremely important for a number of reasons. In the first place the switch mechanism is rather inaccessible for the average garage owner, and secondly the average car operator does not wish to be burdened with continuous upkeep of the overhead door mechanism.

It will also be apparent from the foregoing description that the invention contemplates an overhead door construction requiring minimum headroom for installation. As previously stated, experience has shown that the door will operate satisfactorily when the available headroom is not in excess of two inches. Many of the present day commercial overhead door installations require considerable more headroom in order to accommodate the upper edge, or margin, of the uppermost door section as it is shifted between the curved track portion and the horizontal track portion. The invention contemplates an overhead door construction in which the switch means includes a shiftable switch member and a shiftable latch member for securing the switch member in one position, said latch means being controlled as an incident to the movement of the door sections. That is to say, means is provided which is operable upon movement of the door for shifting the latch member, or means, to permit the shifting of the switch member.

While for purposes of disclosure certain specific structural details have been disclosed herein, it will be apparent that other modifications and changes may be made without departing from the spirit and scope of the appended claims.

I claim:

1. An overhead door construction including a door comprising a plurality of hingedly connected door sections for traversing a door opening, track follower members disposed along opposite side margins of the said door sections and positioned intermediate and at the upper and lower extremities of each side margin of the door, track structures adjacent opposite side margins of the door for accommodating said follower members in directing the door sections between vertical door-closing position and open overhead position, each track structure including an horizontal portion, a substantially vertical portion, and an intermediate curved portion for accommodating said intermediate track followers, a further track portion extending forwardly from each of said horizontal track portions for accommodating the follower member adjacent the upper extremity of the side margin, switch means for selectively connecting said horizontal track portion with said curved track portion and with the said further track portion, said switch means including a shiftable switch member, shiftable latch means for securing said switch member in one position, and means operable upon movement of the door for shifting said latch means to release said switch member.

2. An overhead door construction including a door comprising a plurality of hingedly connected door sections for traversing a door opening, track follower members disposed along opposite side margins of the said door sections and positioned intermediate the upper and lower extremities of each side margin of the door, a track follower adjacent the upper extremity of each side margin of the door, track structures adjacent opposite side margins of the door for accommodating said follower members in directing the door sections between vertical door-closing position and open overhead position, each track structure including an horizontal portion, a substantially vertical portion, and an intermediate curved portion for accommodating said intermediate track followers, a further track portion extending forwardly from each of said horizontal track portions for accommodating the follower member adjacent the upper extremity of the side margin, switch means for selectively connecting said horizontal track portion with said curved track portion and with the said further track portion, said switch means including a shiftable switch member, a shiftable abutment for retaining the switch member in one shifted position, and means operable in response to the movement of the door for shifting said abutment to release the switch member.

3. An overhead door construction including a door comprising a plurality of hingedly connected door sections for traversing a door opening, track follower members disposed along opposite side margins of the said door sections and positioned intermediate the upper and lower extremities of each side margin of the door, a track follower adjacent the upper extremity of each side margin of the door, track structures adjacent opposite side margins of the door for accommodating said follower members in directing the door sections between vertical door closing position and open overhead position, each track structure including a horizontal portion, a substantially vertical portion, and an intermediate curved portion for accommodating said intermediate track followers, a further track portion extending forwardly from each of said horizontal track portions for accommodating the follower member adjacent the upper extremity of the side margin, switch means for selectively connecting said horizontal track portion with said curved track portion and with the said further track portion, said switch means including a shiftable switch member normally urged toward a position which es-

tablishes communication between the horizontal track portion and said further track portion, releasable abutment means for preventing movement of said switch member toward said last mentioned position, and means operable as an incident to the movement of said door for shifting said abutment to release said switch member.

4. An overhead door construction as set forth in claim 1 wherein the latch means includes a pivotally supported member, the pivotal support for which includes an upper bearing surface of restricted cross-section having an open area immediately therebeneath for passage of rust particles and the like from the contacting surfaces of the bearing structure.

5. An overhead door construction as set forth in claim 1 wherein the latch means includes a member having two pivotal points, one for pivotally supporting the member as it is shifted in one direction and the other pivotal support for said member when it is shifted in the opposite direction.

6. An overhead door construction including a door comprising a plurality of hingedly connected door sections for traversing a door opening, track follower members disposed along opposite side margins of the said door sections and positioned intermediate the upper and lower extremities of each side margin of the door, a track follower adjacent the upper extremity of each side margin of the door, track structures adjacent opposite side margins of the door for accommodating said follower members in directing the door sections between vertical door closing position and open overhead position, each track structure including an horizontal portion, a substantially vertical portion, and an intermediate curved portion for accommodating said intermediate track followers, a further track portion extending forwardly from each of said horizontal track portions for accommodating the follower member adjacent the upper extremity of the side margin, switch means for selectively connecting said horizontal track portion with said curved track portion and with the said further track portion, said switch means including a shiftable switch member, shiftable latch means for securing said switch member in one position, a pivotal support for said shiftable switch member including an upper bearing surface of restricted size and an open area therebeneath for passage of rust particles and the like from said bearing surface.

ALVIN V. ROWE.
